UNITED STATES PATENT OFFICE.

BERTHA SCHMITT, OF BROOKLYN, NEW YORK.

WINDOW-GUARD.

SPECIFICATION forming part of Letters Patent No. 276,082, dated April 17, 1883.

Application filed February 20, 1883. (No model.)

To all whom it may concern:

Be it known that I, BERTHA SCHMITT, a citizen of the United States, residing at Brooklyn, in the county of Kings and State of New York, have invented new and useful Improvements 5 in Window-Guards, of which the following is a specification.

This invention consists in a window-guard constructed of two or more wires, the ends of 10 which are bent at right angles and twisted together to form shanks adapted to engage with eyebolts, staples, or other equivalent devices secured in the outside of a window-frame, while the middle portions of the said wires are 15 curved outward in different planes, so as to protect a person engaged in cleaning the outer surface of a window from falling.

In the accompanying drawings, Figure 1 represents a perspective view of my window- 20 guard as applied to a window. Fig. 2 is a similar view of a portion of the same on a larger scale than the previous figure.

Similar letters indicate corresponding parts.

In the drawings, the letter A designates my 25 window-guard, which is constructed of two or more metallic rods or wires, two such rods being shown in the example represented by the drawings. The ends of said wires are bent at right angles and twisted together so as to form 30 shanks a a, while the middle portions, b b, of the wires are bent outward in different planes, as shown. The shanks a a are intended to engage with staples or eyebolts c c, secured in the outside of the window-frame. These staples 35 may be placed at any desired elevation from the window-sill, and several sets of staples may be secured—one above the other—in each window-frame, so that the guard can be adjusted at the required elevation.

The principal advantages of my window- 40 guard are the following:

First, it can be manufactured with comparatively little trouble, and it can therefore be sold at a very low price as compared with other devices for the same purpose. 45

Second, it can be readily removed from one window and adjusted in another one, so that one and the same window-guard will serve for all the windows in a building unless such windows differ considerably in size. 50

Third, it can be used for windows of different size, provided the difference is not more than one or two inches, since the wires composing my window-guard can be readily bent in either direction. 55

Fourth, it forms a good protection for a person engaged in cleaning the outside of a window.

I do not claim broadly as my invention an adjustable and removable window-guard, such as having been made heretofore. 60

What I claim as new, and desire to secure by Letters Patent, is—

A window-guard composed of two or more wires, the ends of which are bent at right angles and twisted together to form shanks a a, while the middle portions of said wires are curved outward in different planes, substantially as shown and described. 65

In testimony whereof I have hereunto set my 70 hand and seal in the presence of two subscribing witnesses.

BERTHA SCHMITT. [L. S.]
